D'OUGREE MARIHAYE, OF OUGREE, BELGIUM

SHEET PILING

Application filed May 14, 1930, Serial No. 452,376, and in Belgium February 6, 1930.

The present invention relates to a novel arrangement of sheet piling to provide a composite wall of caisson sheet piling, with the optional interposition of ordinary sheet piling, using only single **U**, **H** or **Y** shaped members which may be easily made by rolling.

One of the objects of the present invention consists in a new connecting member for use in joining the individual members.

10 Another object of this invention consists in caisson sheet piling having great resistance to bending and permitting progression of the row of sheet piling in the two directions of movement, from a given starting point.

The said improvement consists in the use of a new assembly member or claw for assembling together rigidly the channel shaped sections.

20 This assembly member, which can be rolled, comprises two branches with dove-tailed recesses and a third branch forming a dove-tail tenon.

The invention also relates to the construction of a box shaped sheet piling element by connecting two channel sections rigidly together before they are driven in, by means of two claws such as those specified above, the tenon of one of these claws being if desired provided with a third claw comprising two dove-tailed recesses.

Various embodiments of the invention are illustrated by way of example and in a non-limiting manner in the accompanying drawings.

In the drawings:

Figure 1 shows the form of the assembly member or claw according to the invention.

40 Figures 2 and 3 show two box-shaped sheet piling elements constructed with the claw forming the subject of the invention.

Figure 2 shows the first sheet piling element to be driven in and Figure 3 the subsequent sections.

Figure 4 shows a line of wall comprising both box shaped elements and ordinary elements.

50 Figure 5 shows a modified form of sheet piling formed of box shaped elements, com-

prising a lengthening section for increasing the moment of inertia.

As shown in Figure 1, the claw 5 comprises two branches 5a and 5b with dove-tailed recesses and a third branch 5d in the form of a dove-tail tenon.

It enables, as shown in the following figures, box shaped sheet piling elements to be formed provided with connecting means positioned in such a way as to enable them to be secured to the adjacent sheet piling elements.

The invention provides in particular for the construction as a new industrial product of box shaped sheet piling elements as shown in Figure 3, and formed by rigidly connecting together two channel sections such as 1 before they are driven in, these sections being assembled by means of two claws such as 5, the tenon 5d of one of them being fitted with a claw 2 analogous to the claw described in my said prior specification.

By virtue of this arrangement it is possible to construct easily a line of box shaped sheet piling elements by guiding the open lodgment in the ordinary claw 2 each time over the tenon shaped branch of the claw 5 of the element previously driven in. The first sheet piling element driven in does not comprise an ordinary claw 2 as will be seen in Figure 2.

In Figure 4, which shows a line of sheet piling comprising both box shaped elements and **Z**-shaped elements, it will be noted that in order to connect together a box shaped element and a **Z**-shaped element, use is made of a claw 2' comprising two lodgments the center lines of which form a suitable angle with each other.

In Figure 5 the moment of inertia of the box shaped elements is increased by the use of extension sections 3 placed in alignment with the flanges of the channel sections 1.

What I claim is:

1. For use in the construction of caisson sheet piling by joining before ramming **U**-shaped members having wings terminating in similar ends in alignment with these wings, a **Y**-shaped massive connecting member having two recesses opening in diverging direc-

tions and comprising between them a part of the said massive member and each adapted to encase one of the wing ends of the **U**-shaped members thus spaced apart, and a **5** tenon similar to the wing ends, the median plane of this tenon passing through the intersection of the median planes of the two hollows.

2. For use in the construction of caisson **10** sheet piling by joining, before ramming, **U**-shaped members terminating in trapezoidal ends with their large axis directed along the extension of the wings of these members, a **15** **Y**-shaped connecting member comprising trapezoidal hollows opening in diverging directions and each adapted to house one of the trapezoidal ends of the wings thus spaced apart, and a trapezoidal tenon integral with the **Y**-shaped member, the median plane of **20** which passes through the intersection of the median planes of the other two arms.

3. A caisson pile for forming a row of sheet piling made by rigidly joining, before ramming, two **U**-shaped members with wings **25** terminating in similar ends in alignment with said wings and with their opening and their wing ends arranged face to face, with two **Y**-shaped connecting members which join the wing ends of the **U**-shaped members, **30** each connecting member comprising two hollows opening in diverging directions, and each adapted to encase one of the wing ends of the **U**-shaped members thus spaced apart, and a tenon, similar to the wing ends which **35** extends towards the exterior of the pile, the median plane of this tenon passing through the intersection of the median planes of the two hollows.

4. A caisson pile for forming a row of **40** sheet piling made by rigidly joining, before ramming, two **U**-shaped members with wings terminating in similar ends and in alignment with said wings and with their opening and their wing ends arranged face to face, with **45** two **Y**-shaped connecting members which join the wing ends of the **U**-shaped members, each connecting member comprising two hollows opening in diverging directions, in each of which one of these ends thus spaced **50** apart is housed, and a tenon similar to the wing ends, which extends towards the exterior of the pile, the median plane of this tenon passing through the intersection of the median planes of the two hollows, and a substantially **55** **H**-shaped member comprising two similar hollows, one of which cases the tenon of one of the **Y**-shaped members.

In testimony whereof I have affixed my signature.

CAMILLE BEAUJEAN.
